UNITED STATES PATENT OFFICE.

WALTER B. SCOTT, OF MARBLEHEAD, MASSACHUSETTS.

TOY.

1,396,289.

Specification of Letters Patent.

Patented Nov. 8, 1921.

Application filed April 19, 1920. Serial No. 374,799.

To all whom it may concern:

Be it known that I, WALTER B. SCOTT, a citizen of the United States, residing at Marblehead, in the county of Essex and 5 State of Massachusetts, have invented an Improvement in Toys, of which the following is a specification.

This invention relates to a toy having propelling means comprising an elastic band 10 connected with a stationary component and the axle of the toy and adapted to be stretched by winding it upon the axle whereby to propel the toy by retracting to its unstretched condition.

15 An object of the invention is to so arrange the toy that an ordinary endless rubber band as used for various purposes may be employed as the driving means and in which the band is readily accessible and may 20 be quickly detached from the toy when broken and be replaced by an unbroken band.

Specifically this object of the invention is carried out by looping the endless rubber 25 band over a projection on the driving shaft and a fixed part of the toy, to both of which it is detachably secured, by which the band is separated into two elastic strands adapted to wind equally on the shaft on each side of 30 the projection.

A further object of the invention consists in a novel method of fixing the wheels of the toy to the driving shaft; and other components of the toy together; and specifically 35 a metallic to a non-metallic member.

A further object is generally to improve and simplify the design and construction of a toy of the type above set forth.

Figure 1 is a side view of a toy embodying my invention.

Fig. 2 is a plan bottom view of the toy illustrating the endless elastic band in an unstretched condition.

Fig. 3 is a plan bottom view of the body 45 of the toy illustrating the band wound upon the driving shaft.

Fig. 4 is an end elevation of the toy body illustrating the slotted holder for the band.

Fig. 5 is a detail illustrating the method 50 of detachably securing the band to the shaft.

Fig. 6 is a sectional detail of the driving shaft and a wheel and illustrating the method of fixing the wheel to the shaft.

Fig. 7 is a sectional detail illustrating the

same method applied to another part of the 55 toy.

As here shown my invention is embodied in a wooden toy cart having the body 10 resting on and secured to the two shafts 11 which extend behind the body and have the 60 cross-bar 12 secured to the extended ends, and also extend in front of the body. The front ends of the shaft are drawn inwardly toward each other and are held in fixed relation by the tie-rods 13 in a manner hereinafter to be set forth. A block 14 shaped to simulate some animate being, and in this specific illustration a dog, is disposed between said shafts and supported on said tie-rods. A wheel 15 eccentrically pivoted on 70 the supporting member 16 fixed to the block 14 serves to support the forward end of the toy and causes it to move up and down when the toy is propelled whereby to simulate the natural motion of the animal imitated. 75 Eyelets 17 secured in said supporting member 16 on each side of said wheel and with their flanges adjacent the wheel serve to retain it in place and assist in supporting it. 80

Wooden bearing blocks 18 are secured to the under side of said shafts, about midway under the body and have apertures therethrough. A tubular bearing member or eyelet 19 having an end flange 20 is pressed in 85 the aperture in each bearing block and is adapted to extend beyond the block. Said extended end is turned over to form the outwardly extended flange 21 between which and the opposite flange 20 the bearing block 90 is clamped.

The driving shaft 22 is loosely received in said bearing members and the ends thereof project beyond the body of the toy and 95 wheels 23 are fixed thereto.

Said wheels are formed of thin wood and preferably are built up of a plurality of laminations. It has heretofore been difficult to fasten the wooden wheel to the axle so that it would not wobble and would stay 100 tight thereon, the wheel being thin and of relatively soft material adapted to change its dimensions because of variations of atmospheric conditions. I have found that by my method of uniting the wheel and shaft 105 the two will be permanently rigidly and firmly united.

In carrying out my method, the wheel is

formed with a central aperture therethrough and the metallic tubular member as an eyelet 24 having an end flange 25 is forced therethrough. The end of said member is 5 adapted to extend beyond the body of the wheel and the extended end of said member is upset to form the outwardly extended flange 26. Said flanges are compressed toward each other and thereby are caused firmly to 10 engage the wheel and the tubular member will not become loose therein. The end of the shaft is extended into the tubular member and said tubular member and shaft are soldered together, thereby firmly uniting the 15 wheel to the shaft and causing it to be a component part thereof.

The same method of construction is employed in uniting the tie-rods 13 to the shafts 11. The ends of the shafts are substantially parallel before the block 14 is placed therebetween and the ends are brought toward each other as illustrated in Fig. 2 and held by the tie-rods. Apertures are formed through the ends of the shafts 25 and metallic tubular members or eyelets 27 having the end flanges 28 are forced therein and the extended ends flanged over as for the wheels. The tie-rods are inserted therein and soldered thereto with the result that 30 the shafts are firmly held in position. In some instances the flanges on the eyelets are arranged on the outside of the shafts and the eyelets need not extend entirely through the shafts, for the natural resiliency of the 35 shafts tends to move them apart, and when the tie-rods have been soldered to the eyelets, the flanges will firmly hold the shafts in position.

The propelling means for the toy includes 40 the endless rubber or elastic band 30 of suitable length and thickness and preferably is the ordinary elastic band used for various purposes, whereby band renewals may be conveniently made.

45 As a convenient means for detachably securing the band to the shaft a ring 31 of larger internal diameter than the shaft is arranged thereover and fixed thereto as clearly indicated in Fig. 5, thereby forming a 50 projection of the shaft and providing a space between it and the shaft through which the band is extended for detachable connection with the ring.

A band holder is fixed to the under side

of the cross-bar 12 and comprises a block 55 32 of substantial length but preferably shorter than the distance between said shafts 11 having band-receiving slots 33 in its ends and the band is adapted to be detachably received in said slots. 60

By reason of the substantial distance between the ends of said holder or between the proximate ends of the slots, the band is separated into two distinct strands which will wind equally on each side of the projection of the shaft, as illustrated in Fig. 3. 65

By this construction sidewise strains on the driving shaft, present in other structures are obviated.

The band is under the body of the toy and 70 is freely accessible.

I claim:

1. The combination in a toy, of a rotatably supported shaft having band-engaging means, a fixed support carried by the frame 75 of the toy, and an endless elastic band detachably connected with said fixed support and band-engaging means, said support and band-engaging means coöperating to separate said band into two spaced strands 80 adapted independently to wind about said shaft.

2. The combination, in a toy, of a rotatably supported shaft, having a projection, a fixed support having two spaced band-supporting portions, and an endless elastic band detachably secured to said projection and detachably secured over said spaced supporting portions of said support and separated by said support into two separate 90 divergent strands adapted to wind about said shaft spirally on opposite sides of said projection. 95

3. The combination, in a toy, of a body, a shaft having a projection intermediate its 100 ends, spaced-apart bearings rotatably supporting said shaft on opposite sides of said projection, an endless elastic band detachably secured to said projection, and a fixed support for the band carried by said body having slots in its ends in which the band is detachably received by which it is divided into two strands each adapted to wind about said shaft.

In testimony whereof, I have signed my 105 name to this specification.

WALTER B. SCOTT.
